UNITED STATES PATENT OFFICE

JAMES B. JARMIN, OF DALLAS, TEXAS

ROAD MACHINE

Application filed January 10, 1929. Serial No. 331,605.

This invention relates to new and useful improvements in road machines.

Road machines such as scrapers, graders and the like must be built with comparatively long wheel bases on account of the long blades required to work on the wide roads now built and also because of the necessary angular adjustments of such blades. The blades are suspended from a frame carried by front and rear wheels and owing to the long wheel base, such frames must be constructed of heavy longitudinal beams or channels spaced apart and adequately braced to endeavor to neutralize the torsional and carrying strains. 15 There are many disadvantages attached to such frames. In order to secure strength heavy members must be used and this adds unnecessary weight. The frames are frequently three or four feet wide and with 20 their cross braces obstruct the operator's view of the blade. The expense of constructing such frames is a large item in the cost of producing the machines.

One object of the invention is to construct 25 a road machine with a single longitudinal central reach of tubular or equivalent structure, whereby the disadvantages of the usual frame are eliminated and a more simple, compact and less expensive blade support is produced.

A further object of the invention is to provide a central longitudinal member connecting the front and rear axles and which will be much stronger than the usual frame and 35 which will better resist the load and torsional strains.

Another object of the invention is to provide a supporting and connecting member 40 permitting of less weight in the machine, affording a better observation of the blade and work by the operator and making for simplicity in the assembly of the machine.

Still another object of the invention is to 45 provide a simple, efficient and advantageous

connection of the reach and the rear platform of the machine.

A further object of the invention is to provide a blade carrier adjusting and supporting assembly having a unitary mounting on the 50 reach.

Further reference will be made herein to the foregoing and other features of the invention, which will be more particularly pointed out.

In the following specification an exemplification of the invention is set forth and this is illustrated in the accompanying drawings in which:

Fig. 1 is a side elevation of a road machine 60 constructed in accordance with the invention,

Fig. 2 is a plan view of the same,

Fig. 3 is an enlarged transverse sectional view taken on the line 3—3 of Fig. 2,

Fig. 4 is an enlarged transverse sectional 65 view on the line 4—4 of Fig. 2,

Fig. 5 is a sectional view of the locking and adjusting means for the blade hanger ring,

Fig. 6 is a detail of the rear axle adjusting means,

Fig. 7 is a rear elevation of the machine,

Fig. 8 is a detail of the steering gear,

Fig. 9 is a side elevation of the same, and

Fig. 10 is a transverse sectional view showing the frame shifting means.

In the drawings the numeral 10 designates a main connecting member or reach which connects the front and rear axles and constitutes the backbone of the machine. It is the essence of the invention to form this reach as a single central member extending longitudinally and being tubular or hollow so as to give strength and rigidity. It is preferable to use for this reach a length of pipe of comparatively large diameter.

As an illustration, it has been found that a 12 inch pipe 16 feet long will safely carry a load of 54,000 pounds and the twisting strength of this size of pipe is approximately 84,000 pounds on an average of 10 feet in

length. A machine constructed with this size of pipe would weigh less than 10,000 pounds and, therefore, the reach has an ample load carrying and torsion resisting capacity.

5 In carrying out the idea of simplicity and practical construction the reach is provided with an annular flange 11 at its rear end which is bolted to the flange 12 of an elbow 13 preferably of the same diameter as the pipe. The elbow has a base flange 14 which is secured by bolts 15 upon a rear platform 16. It is not considered necessary to go into details of construction which are in common use and are now being manufactured for the trade. It will be sufficient for the purpose of the invention to say that the platform 16 is suitably mounted on a rear axle 17 so as to be shifted laterally on said axle, 15 whereby said axle may be swung in a horizontal plane. These features and the means for accomplishing the results form no part of the invention. The rear axle is mounted in ground wheels 18.

20 25 At its forward end the reach pipe 10 is carried by a post 19 having a saddle 20 at its upper end. A cap 21 (Figs. 3 and 9) is secured to the saddle by bolts 22 and the forward end of the pipe is clamped in the saddle by the cap. The saddle and cap are provided with lugs 23 engaging in apertures 24 in the pipe, whereby said pipe is held against circumferential movement when clamped in position.

30 35 A front axle 25 is supported in ground wheels 26. An arched cross member 27 has its lower ends secured to the front axle adjacent the ground wheels. The post 19 is formed with a circular plate 28 on its bottom, which engages on a circular boss 29 on the member 27, whereby a turn-table is formed. A king pin 30 passes through the bosses and is secured by collars 31. A clevis plate 32 is loosely pivoted on the pin 30 within the post 19 and is held against upward displacement by a collar 33 fastened on said pin, as is best shown in Fig. 3.

40 45 50 55 A longitudinal sub-frame 34 underlies the reach 10 and has its forward end rigidly attached to the clevis plate 32. This frame, by reason of the pivotal mounting of said plate, may be raised and lowered at its rear end or swung in a transverse arc on its longitudinal axis. The frame is composed of side angle members extending rearwardly from the plate 32 and curving outwardly from each other at their rear ends. The rear ends of the frame members are connected by a cross angle bar 35.

60 65 The reach 10 is also attached to the front portion of the rear platform 16 by a standard 36 carrying a clamp 37, whereby said reach member is securely fastened. In order to support the rear end of the sub-frame 34 an adjustable hanger is fastened on the reach. 70 75 80 85 90 95 100 105 110 115 120 125 130 135

tending hanger brackets 38 which are in the form of castings having semi-circular clamp collars 39 at their inner ends. The clamp collars engage on each side of the reach and are connected by top and bottom bolts 40. As is shown in Fig. 4, each collar has a plurality of lugs 41 engaging in apertures 42 in the reach, whereby the brackets are supported against circumferential movement on the pipe.

Each bracket 38, as is best shown in Fig. 4, is bifurcated for receiving a segmental gear 43 formed integral with a rocker 44 journaled on a shaft 45. Each rocker includes an arm 46 and a grooved segment 47 concentric to its shaft 45. The outer end of each rocker arm carries a journal box 48 engaging in a hanger loop 49 and receiving a transverse pivot bolt 50, which is vertically adjustable in apertures 51 in said loop whereby the hanger loop may be set at different elevations. Each hanger loop has a universal joint 52 at its lower end which is pivoted in a box 53 secured to the rear side of the frame member 35.

It will be seen that the frame 34 is freely hung for vertical adjustment both longitudinally and transversely and also for tilting or rotative adjustment on its longitudinal axis. For adjusting the rockers 44 the segmental gears 43 are driven by worm screws 54 journaled in the brackets 38, as is shown in Fig. 4. Each worm screw has a bevelled gear 55 on its upper end which is driven by a bevelled gear 56 on the forward end of an adjusting shaft 57. The adjusting shafts extend rearwardly on each side of the reach 10 and are journaled in a support 58. Each shaft has a bevelled gear 59 on its rear end driven by the bevelled gear 60 formed on the hub of a hand wheel 61 loosely journaled on a shaft 62. By revolving either hand wheel the worm screw 54 associated therewith is rotated and the segmental gear 43 is swung, whereby the rocker 44 is actuated and the hanger loop 49 is either raised or lowered.

As will be hereinafter explained the sub-frame 34 carries the scraper blade and a heavy load. In order to make for easy adjustment of the rockers, cables 63 have their ends seated in the grooved segments 47 and pass over pulleys 64 journaled on the brackets 38. Each cable is extended forwardly over the reach 10 and secured to the rear end of a heavy coiled spring 65. The coiled springs are connected at their forward ends (Figs. 1 and 2) with eye bolts 66 secured in a transverse bracket 67 rigidly mounted on the reach member 10.

The springs are constantly under tension and when the rockers are actuated to lower the loops 49 the springs are further tensioned, and thus when the operation is reversed to raise the hanger loops the springs assist the rockers in elevating the load. It is pointed out that the entire hanger assembly is

clamped upon the reach member by the bolts 40, thus making for simplicity in assembling the machine.

On the front side of the rear platform 16 I 5 mount a carriage 68 on a slide 69. The slide is connected in an endless chain belt 70 passing over pulleys 71 mounted on each side of the rear platform. One of the pulleys is fastened on the front end of a shaft 72 mounted 10 on one side of the rear platform and carrying a worm gear 73 on its rear end (Figs. 7 and 10) which is actuated by a worm screw 74 rotated by a hand wheel 75 at the right of the driver's position on the rear platform. The 15 carriage, as is shown in Figs. 10 and 11, has swivelled connection at 76 with a pilot pin 77 journaled in the rear end of a radius brace or strut 78 having its forward end hinged to the rear side of the frame member 35.

20 When the sub-frame 34 is adjusted to any position the strut 78 will be likewise adjusted because of its freedom in sliding or rotating on the pilot pin 77. Likewise, by rotating the shaft 72 through the agency of the hand 25 wheel 75 the chain 70 is adjusted whereby the carrier 68 is shifted laterally, which results in a lateral shifting or swinging of the rear end of the frame 35 because of the pivotal suspension of said frame. The rear of the sub- 30 frame may be shifted laterally to any position by the hand wheel 75 and its elevation and inclination controlled by the hand wheels 61.

A blade ring 79 is suspended from the sub-frame 34. The rear portion of the ring 35 is supported by a transverse hanger bar 80 engaging under the lip of the ring, while the forward end is supported as shown in detail in Fig. 5. The front support includes a 40 transverse bracket 81 on which the lip of the ring rests. A spring pressed plunger pin 82 carried by the bracket 81 engages the teeth 83 on the lip of the ring and holds said ring against rotation. To release the ring a wedge 84 slideable through the pin is operated by a 45 rod 85 to elevate said pin from the teeth. When the ring 79 is unlatched it may be adjusted by means of a pinion 86 which engages teeth 87 on the bottom of the ring. The pinion is mounted on a shaft 88 journaled 50 in the bracket 81. This shaft is connected by means of a universal 89 with an adjusting shaft 90 having a hand wheel 91 for operating the same. A blade 92 is suspended by standards 93 from the ring and is adjusted thereby. 55 It is obvious that the blade may be swung to any necessary angle.

Various changes in the size and shape of the different parts, as well as modifications and alterations, may be made within the scope of 60 the appended claims.

What I claim, is:

1. In a road machine, a longitudinal pipe reach, a front axle mounted in ground wheels, a support carried by the front axles and secured to the front end of the pipe, a surface

working tool carried by the pipe, an elbow secured to the rear end of the pipe, a rear platform connected with the elbow, and a rear axle mounted in ground wheels and supporting the platform. 70

2. In a road machine, a longitudinal pipe reach, a front axle mounted in ground wheels, a support carried by the front axles and secured to the front end of the pipe, transverse hangers clamped around the pipe, links adjustably carried by the hangers, a blade carrier connected with said links, a blade carried by said carrier, an elbow secured to the rear end of the pipe, a rear platform connected with the elbow, and a rear axle mounted in ground wheels and supporting the platform. 75

3. In a road machine, an upright front support mounted on wheels, an elongated pipe member clamped to the front support, 80 a blade hanger clamped on the pipe member and held against rotation thereon, a rear platform supported on ground wheels, and means for securing the pipe member to the platform. 90

4. In a road machine, an upright front support mounted on wheels, an elevated elongated pipe member clamped to the front support, a sub-frame having its forward end swiveled in the front support, a hanger clamped against rotation on the pipe member and adjustably supporting the rear end of the frame, a scraper blade carried by the frame, a rear platform supported on ground wheels, and means for securing the pipe member to the platform. 95

5. In a road machine, an upright front support mounted on wheels, an elevated elongated pipe member clamped to the front support, a sub-frame having its forward end swiveled in the front support, a hanger clamped against rotation on the pipe member and adjustably supporting the rear end of the frame, a scraper blade carried by the frame, a rear platform supported on ground wheels, means for securing the pipe member to the platform, and adjusting means mounted on the platform and attached to the sub-frame for shifting the same laterally. 105

6. In a road machine, the combination with a wheel-supported longitudinal reach pipe, of a pair of laterally extending hanger brackets bolted on each side of said reach, means on the brackets engaging the reach pipe for preventing circumferential movement of the parts, rockers carried by the brackets, and a scraper blade suspended from the rockers. 115

7. In a road machine, the combination with a wheel-supported longitudinal reach pipe, of a pair of laterally extending hanger brackets bolted on each side of said reach, means on the brackets engaging the reach pipe for preventing circumferential movement of the parts, rockers carried by the brackets, a scraper blade suspended from the 120 125 130

rockers, and spring tensioned compensating means connected with the rockers for compensating the load on the rockers.

8. As a sub-combination in a road machine, 5 a blade hanger including a pair of brackets having means for clamping together on a single central support, rockers mounted in the brackets and having segmental gears, worm screws in the brackets engaging said gears, 10 and hanger loops pivoted on the ends of the rockers.

9. As a sub-combination in a road machine, 15 a blade hanger including a pair of brackets having means for clamping together on a single central support, rockers mounted in the brackets and having segmental gears, worm screws in the brackets engaging said gears, grooved segments integral with the rockers, 20 cables connected in said grooved segments, and compensating springs to which said cables are attached.

10. In a road machine, a longitudinal pipe 25 reach, a front axle mounted in ground wheels, a support carried by the front axle and secured to the front end of the pipe reach, a surface working tool carried by the pipe reach in rear of the front axle, an elbow secured to the rear end of the pipe reach, and a rear axle mounted in ground wheels 30 and connected with the elbow.

11. In a road machine, an upright front support mounted on wheels, an elongated pipe member secured to the front support, a blade hanger clamped on the pipe member and held 35 against rotation thereon, a rear axle mounted in wheels, and an upright support carried by the rear axle and secured to the rear end of the pipe member, whereby the pipe member is elevated a substantial distance above 40 the rear axle, the pipe member constituting the sole support for the hanger as well as the sole connection between the front and rear axles of the machine.

12. In a road machine, a front axle, a front 45 support carried by the axle and extending upwardly therefrom, front wheels supporting the axle, a single central longitudinal tubular reach having its front end fastened to the front support, a rear axle, ground 50 wheels supporting said rear axle, a rear support carried by the rear axle and extending upwardly therefrom, the rear end of the reach being connected to the rear support, a hanger clamped around the reach intermediate 55 its ends, supporting elements suspended from the hanger on each side of the reach, a tool frame supported by the lower ends of the elements, and a surface working tool carried by the frame.

60 13. In a road machine, a front axle, a front support carried by the axle and extending upwardly therefrom, front wheels supporting the axle, a single central longitudinal tubular reach having its front end fastened to 65 the front support, a rear axle, ground wheels

supporting said rear axle, a rear support carried by the rear axle and extending upwardly therefrom, the rear end of the reach being connected to the rear support; a hanger clamped around the reach intermediate its ends, supporting elements suspended from the hanger on each side of the reach, a tool frame extending longitudinally under the reach and having its front end carried by the front support and its rear end carried by the supporting elements, and a surface working tool carried by the frame.

In testimony whereof I affix my signature.

JAMES B. JARMIN.
